J. E. RABER

WINDOW GUARD

Filed Aug. 26, 1924

Patented Sept. 22, 1925.

1,554,366

UNITED STATES PATENT OFFICE.

JOHN E. RABER, OF CANTON, OHIO.

WINDOW GUARD.

Application filed August 26, 1924. Serial No. 734,359.

To all whom it may concern:

Be it known that I, JOHN E. RABER, a citizen of the United States, residing at Canton, in the county of Stark and State of Ohio, have invented certain new and useful Improvements in Window Guards, of which the following is a specification.

The invention relates to improvements in protectors or guards for windows, and has more especial reference to a guard particularly adapted for use upon the swinging sash of a coal cellar window, and the present invention is an improvement over my prior Patent No. 1,213,537, dated January 23, 1917.

The objects of the improvement are to provide a guard or protector which will protect the glass panel of the swinging sash when the same is in the open position and which will automatically swing downward away from the glass panel when the sash is moved into the closed position, permitting the light to pass through the glass panel.

The above and other objects may be attained by constructing the guard in the manner illustrated in the accompanying drawing, in which—

Figure 1 is a perspective view of a coal cellar window having a swinging sash provided with the improved guard, showing the sash in the open position.

Fig. 2, an interior elevation of the coal window, showing the sash in the closed position and the guard in the normal lowered position;

Fig. 3, a transverse sectional view showing the parts in the same position as in Fig. 2;

Fig. 4, a similar view showing the sash in the open position and the guard in position to protect the glass panel; and

Fig. 5, a detail perspective view of the brackets upon the sash which support the guard.

Similar numerals refer to similar parts throughout the drawings.

The frame of the cellar window is shown at 5 and may be provided with the stationary hinge ears 6 to which the movable hinge ears 7 of the swinging sash 8 are connected, the hinge being preferably of the construction shown in my prior Patent No. 1,193,058, issued August 1, 1916.

The window frame may be provided with the chute 9 of any usual construction within which is pivotally mounted a hopper 10 which may be of the form disclosed in my co-pending application filed of even date.

A glass panel 11 is provided in the swinging sash 8 and arranged to be protected by the window guard 12 when the sash is in the open position as shown in Figs. 1 and 4.

This guard is in the form of a heavy sheet 60 or plate of metal, slightly larger than the glass panel and provided along one horizontal edge with the half round bars 13, which may be riveted or otherwise secured thereto.

A pair of spaced brackets 14 and 15 are fixed 65 upon the inner side of the swinging sash, near the lower edge thereof and provided with the angular ears 16 and 17 respectively. The ear 16 is provided with a keyhole slot 18 and the ear 17 is provided with a substantially 70 keyhole-shaped slot 19 opening at its larger end into a notch 20.

The half round bar 13 is of substantially the width of the narrow portions of the slots 18 and 19 and has a diameter substantially 75 the same as the diameters of the enlarged portions of said slots.

Thus when the sash is in the opened position, as shown in Figs. 1 and 4, the half round bar 13 drops into the reduced portions 80 of the slots 18 and 19 and is held against turning movement therein, the guard plate 12 being positioned over the glass panel 11, protecting the same against injury from coal or the like, which may be thrown into the 85 chute from the outside.

As the sash is closed, the guard will be held in the same relative position until the sash assumes the closed position, as shown in Figs. 2 and 3, at which time the weight 90 of the guard plate will cause the half round bar 13 to drop into the enlarged portions of the keyhole slots when the bar is free to rotate; the guard plate dropping by its own weight away from the glass panel and going 95 to rest upon the bottom of the chute, as shown in Figs. 2 and 3.

In the same manner as the swinging sash is opened, the guard plate will assume a substantially vertical position, the half round bar 13 rotating in the enlarged portions of the keyhole slots as the sash is raised, and as the sash assumes the fully opened position, shown in Figs. 1 and 4, the half round bar will slide downward into the 100 reduced portions of the keyhole slots, holding the guard plate in position over the 105 glass panel.

A latch 21 may be provided upon the 110 swinging edge portion of the sash and arranged to be released by a cord or other

flexible member indicated at 22, and extended to a convenient point inside of the coal window.

From the above, it will be obvious that a simple and efficient guard is provided to protect the glass panel of the swinging sash.

- Although the guard disclosed in my prior Patent No. 1,213,537 is efficient and practical, it is evident that more mechanism is necessary to control the automatic opening and closing of the two piece guard plate shown therein, than is necessary in the present case.
- 15 While the guard to which the present application pertains comprises a single sheet or plate having a connection to the swinging sash at one edge only, the operation of the guard plate is automatic with the opening and closing of the swinging sash.

I claim:

1. A window guard of the character described, including a sash hinged at one horizontal edge, a guard plate hingedly connected at its upper edge to said hinged sash and means in the hinge of the guard plate for holding the guard plate parallel to the sash in the open position, and until the sash reaches substantially the closed position and for permitting the guard plate to swing away from the sash in the closed position.
2. A window guard of the character described, including a sash hinged at one horizontal edge, a glass panel in the sash, a guard plate hingedly connected at its upper edge to the swinging edge of the sash and

means in the hinge of the guard plate for holding the guard plate over the glass panel when the sash is in the open position, and until the sash reaches substantially the closed position and for permitting the guard plate to swing away from the glass panel when the sash is in the closed position.

3. A window guard of the character described, including a sash hinged at one horizontal edge, a glass panel in the sash, ears at the swinging edge of the sash and provided with keyhole slots and a guard plate provided at its upper edge with flat side 50 pintles located in said keyhole slots, whereby the guard plate is held over the glass when the sash is in the open position and until the sash reaches substantially the closed position and is permitted to swing 55 away from the glass when the sash is in the closed position.

4. A window guard of the character described, including a sash hinged at one horizontal edge, a glass panel in the sash, ears 60 at the swinging edge of the sash, and provided with keyhole slots, a guard plate having a half round bar at one horizontal edge, the ends thereof being located in the keyhole slot, whereby the guard plate is held 65 against the glass panel when the sash is opened and until the sash reaches substantially the closed position, and is permitted to swing away from the glass panel when the sash is closed.

In testimony that I claim the above, I have hereunto subscribed my name.

JOHN E. RABER.
